TENT

James C. Pyatt, Dayton, Ohio, assignor of one-half to Josephine L. Bossard, Dayton, Ohio

Application November 6, 1935, Serial No. 48,521

11 Claims. (Cl. 135—4)

This invention relates to tents and more particularly to tents having a folding framework.

One object of this invention is to provide a tent which may be very readily put up and taken 5 down.

Another object of this invention is to provide a tent having a unitary frame structure with a covering attached to the frame and foldable with the frame, so that the tent may be stowed complete. 10

Another object of this invention is to provide a tent frame having jointed parts all of which remain connected as the frame is put up or taken down.

15 Other objects and advantages of the invention will be apparent from the following description, the appended claims, and the accompanying drawings.

In the drawings, in which a preferred embodiment of the invention is shown,

20 Fig. 1 is a perspective view of the tent, with the netting cover, the storm top, and the storm side partially broken away to show the frame structure of the present invention;

25 Fig. 2 is a plan view of the top arm connecting member or hub;

Fig. 3 is an elevational view of the hub;

Fig. 4 is a perspective view of the side arm connection member;

30 Fig. 5 is a detail of the connection between a top arm and a side arm, shown partly in section;

Fig. 6 is a vertical transverse section of a portion of the frame in partly folded position; and

35 Fig. 7 is a vertical section corresponding to Fig. 6, but showing the frame in a set-up position.

In the drawings, in which like numbers refer to like parts throughout the several views, the invention is shown as a tent having a covering of netting or similar material as a protection

40 against insects, and also having an additional weather protection which can be used if desired. It will be understood that a tent or similar construction having a greater or lesser number of sides than that illustrated may be used without departing from the scope and spirit of the invention.

The tent frame in accordance with the present invention, can be readily folded and spread or put up. This frame includes elements that are 50 interconnected as by simple hinge connections permitting folding and unfolding movements without disassembly or disconnection of the elements. Where a covering of mosquito netting is used the covering may remain attached to the frame elements and collapsed or put up with

the collapsing or erecting movements of the frame. The tent frame includes a top connecting member or plate designated generally by the numeral 10, top arms 11 radiating from this top plate, and side supports 12 depending from the outer ends of the top arms 11. The interconnections of these parts is such that as they are unfolded they move into proper position so that the top connecting member 10 is elevated and the top arms 11 which radiate from it define 10 the top of the structure, and the side supports 12 define the sides, the outer end of each top arm being supported by a pair of side supports which diverge downwardly with the bottom end of each side support connected with the bottom end of 15 the adjacent side support of the next pair.

The pivotal interconnection of all the frame parts permits folding of the frame without any disassembly, to form a compact bundle. When folded, the top connecting member is positioned 20 down inside the side supports, which are drawn in and closely surround the top connecting member in positions approximately paralleling each other; and the top arms extend downwardly, lying within the now closely grouped side supports 25 and nearly parallel to each other and to the side supports. The interconnection of parts which contributes to the advantages set out above includes hinge connections between the top connection member and the top arms, and means 30 defining the set-up position of the top arms, hinge connections joining the outer end of each top arm with its associated pair of side supports, and hinge connections at the lower ends of the side supports joining them in the order chosen. 35 The construction and operation of one embodiment of this invention will now be described in detail.

The top connecting member 10, from which the top arms 11 radiate, is preferably constructed as 40 a casting having its lower portion formed as a stop surface or disk 13. Projecting up from surface 13 is a hub portion 14 of smaller diameter than the stop surface 13. The hub portion has formed in it a plurality of recesses 15, opening 45 radially outwardly and upwardly. The portion of disk 13 which extends beyond hub 14 slopes downwardly away from the hub, the angle of slope governing the position of top arms 11 when the tent is set up, since these top arms are pivoted 50 one in each recess of the hub, and are located against the stop surface when the tent is erected.

The upstanding lugs 16 between the recesses 15 have notches 17 cut in their tops. These notches are placed toward the rear of the top 55

openings of recesses 15 and receive in them the ends of pivot pins 18 on which top arms 11 are pivoted at their inner ends. It is preferred to extend these notches straight across lugs 16 from one recess to the next, and to make them enough larger than pivot pins 18 so that the pins, although resting in two notches lying at an angle to each other, may still assume their normal position necessary to allow top arms 11 to extend radially. These pins are held in place by cap plate 19 which is about the same diameter as hub 14 and which is notched to correspond to the upper openings of recesses 15. Cap 19 and hub 14 are centrally bored to receive bolt 20, which holds the parts assembled. The disk 13 and hub 14 may be cast integrally from a light weight metal.

Top arms 11 are preferably made of wood, but may be reinforced or sheathed with metal from their inner ends to the point where they contact with stop disk 13 when the tent is erected; this sheathing also reinforcing the bores which receive pivot pins 18, as well as reinforcing the top arms where they contact with disk 13. The positioning of pivot pins 18, the shape of recesses 15 and the slope of disk 13 on its upper side are all coordinated to give adequate support to top arms 11 when in extended position, and are likewise proportioned to give the desired shape to the tent, and the desired components to the tension springs to be described below.

The outer ends of each top arm 11 are enclosed by a sheet metal clip 24 of a connection means designated generally by reference numeral 23. Two similar clips embrace the upper ends of a pair of side supports 12. Each clip tightly embraces the end of an associated arm, small tacks serving to prevent endwise movement of the clips. The two clips of the side supports are pivotally interconnected for relative movement on a horizontal axis by means of a horizontally extending eye bolt 25, the eye portion of which receives a bolt 25' which passes horizontally through the clip 24 of the top arm 11. A pair of downwardly diverging side supports 12 is thus attached to the outer end of each top arm 11 so that any of the connected arms can move relatively to either of the others. The side supports are preferably constructed of wood, and in a tent of preferred proportions will be somewhat longer than top arms 11. These side supports extend downwardly and outwardly from top arms 11 and have their bottom ends joined at 26 each side support being pivotally connected to the adjacent side support of the next pair. Except for the two side supports between which the entrance is cut, the bottom ends are joined by lower pivotal connections including clips of metal like the clips 24 which clamp around the lower ends of side supports 12, and which are pivotally interconnected by a pivot bolt.

To provide a doorway for the tent, the bottoms of two side supports extending downwardly from two adjacent top arms 11 are spaced apart a distance somewhat less than the distance between the outer ends of the two top arms by a threshold assembly 27. The lower ends of these side supports are connected in the same way as the others, as by clip pieces 29 pivotally interconnected for attachment to the other ends of the two threshold rods 29 which are of equal length and are pivoted together. This construction allows the threshold pieces 29 to swing upwardly during folding.

75 The tent is held both in its set-up or erected

position by a spring 33, there being a spring section between each two top arms 11. These springs are fastened to the lower sides of the top arms 11 a short distance beyond the edge of disk 13 and together form a ring of springs 5 surrounding this disk. Because of the inclination of the upper face of disk 13, together with the positioning of pivot pins 18, when the arms are in set-up position they are sufficiently inclined from the horizontal so that the pull of 10 springs 33 has a vertical component sufficient to hold the arms in their set-up position, and consequently to maintain the entire tent structure in its erected position. As soon as a folding operation takes place, however, the springs 33 15 pull the top arms 11 together into a compact bundle, and the side supports 12 are in turn pulled inwardly, due to the action of the pivot connections at 23.

The covering of the tent may be secured to 20 the framework so as to fold with it. In the mosquito tent shown, the covering includes a canvas floor 35, which is tacked or bound at each joint 26 to the framework. This floor may be held spread as by rings 36 which may receive 25 a small stake or a guy rope. The sides and top are covered by netting 38 which is stitched to the floor 35 and tacked or fastened at the tops of side supports 12. It is preferred to reinforce this netting where it overlies the connections 24 30 between the top arms and the side supports, and also where it overlies the top plate 10. In addition the tent may be equipped with a storm top 37 which is removably fastened, as by snap fasteners, to the side arms at their upper ends. 35 Storm sides 39 may likewise be provided and likewise removably attached. These storm sides and top are made from heavy canvas, and the top includes a depending flap which overlies the storm side and covers the joint between the two. 40 Entrance to the tent may be provided by a sliding fastener inserted in the netting covering between the two side supports connected by the threshold pieces 29, and the storm side may have the usual tent flaps. In addition the tent may 45 be equipped with a canvas carrying bag of proper size to hold the entire tent when in folded position.

The tent while folded has a roughly cylindrical shape, its length being approximately that 50 of the length of the side pieces and its diameter slightly greater than the diameter of top plate 10. To erect the tent the bottoms of the side supports are spread out and the threshold pieces unfolded. It is then possible to reach in through 55 the doorway of the tent and push upwardly on the bottom of connecting member 10, and as the latter is pushed beyond the position in which the top arms 11 extend radially, springs 34 exert a pull which holds the top arms in contact with 60 disk 13, and holds the entire tent in position. It only remains to make some slight adjustment of the bottoms of the side supports, as they may not have reached their fully extended position due to the play or slack in the pivot connections. 65 Folding of the tent is equally simple and comprises merely the reverse operations, it being only necessary to pull down on top plate 10, and the top arms 11 will then be drawn to their folded position by springs 33, pulling with them 70 side supports 12. The bottoms of the side supports are then gathered together.

While the form of apparatus herein described constitutes a preferred embodiment of the invention, it is to be understood that the invention is 75

not limited to this precise form of apparatus, and that changes may be made therein without departing from the scope of the invention which is defined in the appended claims.

5. What is claimed is:

1. A frame of the character described comprising a top member, arms connected to said member, stop means defining a spread position of the arms, supports for the ends of said arms 10 and yieldable means urging the arms against said stop means when the frame is set up, but urging the arms toward folded position away from said stop means during folding.

2. A tent comprising a foldable frame adapted 15 for the support of a frame covering, said frame including a top member, radial arms pivoted to said top member, each arm having movement in a vertical plane, stop means defining the position of the arms with respect to the top member 20 when the tent is set up, side supports attached to said arms, and yieldable means urging the arms against said stop means when the tent is set up.

3. A tent comprising a foldable frame adapted 25 for the support of a frame covering, said frame including a top plate, top arms pivoted to said top plate, stop means defining the position of the top arms with respect to the top plate when the tent is set up, side supports attached to said 30 top arms, and yieldable means urging the top arms against said stop means when the tent is set up, but urging the top arms toward folded position away from said stop means during folding.

35. 4. A tent comprising a foldable frame adapted for the support of a frame covering, said frame including a top plate, top arms pivoted to said top plate, stop means defining the position of the top arms with respect to the top plate when 40 the tent is set up, a plurality of pairs of side supports the upper ends of each pair being pivotally attached to the outer end of each top arm, the lower end of each side support being connected to the lower end of the adjacent side 45 support of the next pair, and means holding said top arms against said stop means.

5. A tent comprising a foldable frame, said frame including a top plate, top arms movably connected to said top plate, and a plurality of 50 pairs of side supports, the top ends of each pair having a pivotal interconnection with the outer end of a top arm and extending downwardly therefrom, the lower end of each side arm being pivoted to the lower end of the adjacent side 55 arm of the next pair.

6. A tent frame comprising a series of radially extending top arms, a pair of upwardly converging side arms for each top arm, and a connecting means pivotally interconnecting the outer end 60 of a top arm and the upper ends of a pair of side arms for relative movement of the side arms on a horizontal axis and for movement of the top arm relatively to either side arm on a horizontal axis.

65. 7. A tent comprising a foldable frame, said frame including a top plate, top arms movably connected to said top plate, and a plurality of pairs of side supports, connecting means piv-

otally connected to the top ends of each pair and to the outer end of a top arm and providing for movement of all of said arms and supports into substantial parallelism, and means pivotally connecting the lower end of each side support to the lower end of an adjacent side support of the next pair on a horizontal axis.

8. In a tent, a top member having a hub portion provided with recesses opening radially and upwardly, said top member having a portion extending beyond said hub and having a stop surface, top arms each having one end pivoted to said top member in one of said recesses, side supports each pivoted to the outer end of a top arm, and means urging said top arms into contact with the stop surface of the top member.

9. In a tent, a top member having a hub portion provided with recesses opening radially and upwardly, part of said top member extending beyond said hub portion and having an inclined lower surface, top arms each having one end pivoted for movement in one of said recesses, a plurality of pairs of downwardly extending side supports, connection means pivotally interconnecting the outer end of each top arm with the upper ends of a pair of side supports, means joining the lower end of a side support with the lower end of the adjacent side support of the next pair, door spacing means pivotally joining in spaced relationship two adjacent side supports 30 at their lower ends, the upper ends of said two side supports being attached to adjoining top arms, and a common spring normally urging all said top arms into contact with said inclined surfaces of the top plate to hold the tent spread, 35 said spring being connected to said top arms at a distance from said inclined surfaces to urge the frame toward collapsed position after the top member is lowered a predetermined amount.

10. In a tent frame, a top arm, a pair of upwardly converging side supports connected at their upper ends at a common point to said top arm for the support of the outer end of the top arm, and means pivotally connecting said side supports and top arm for relative movement of the side supports on a substantially horizontal axis corresponding generally to the longitudinal axis of said top arm and for relative movement of the top arm with respect to the side supports about a second horizontal axis which is substantially transverse to the first said horizontal axis.

11. In a tent frame, a top arm, a pair of upwardly converging side supports connected at their upper ends at a common point to said top arm for the support of the outer end of the top arm, and means pivotally connecting said side supports and top arm for relative movement of the side supports on a substantially horizontal axis corresponding generally to the longitudinal axis of said top arm and for relative movement of the top arm with respect to the side supports about a second horizontal axis which is substantially transverse to the first said horizontal axis, said connecting means having relatively movable portions clamping around the ends of the 60 connected arms and supports.

JAMES C. PYATT.
